REFRIGERATOR LATCH

Hal W. McPherson, Dayton, Ohio, assignor, by
mesne assignments, to General Motors Cor-
poration, a corporation of Delaware

Application October 31, 1931, Serial No. 572,421

6 Claims. (Cl. 292—173)

This invention relates to refrigerating apparatus and more particularly to latches for the doors of refrigerator cabinets for use with refrigerating apparatus.

5 The objects of my invention include the providing of an improved and relatively noiseless latch means for a refrigerator door in which the major portion of the mechanism is concealed within the door and is readily assembled in place 10 and also removed therefrom; and the providing of means for sealing of a concealed latch for preventing the access of external air and moisture to the concealed mechanism.

Further objects and advantages of the present 15 invention will be apparent from the following description, reference being had to the accompanying drawing, wherein a preferred form of the present invention is clearly shown.

In the drawing:

20 Fig. 1 is a fragmentary sectional view of a portion of a refrigerator cabinet disclosing my improved latch mechanism;

Fig. 2 is a fragmentary view of the side of the door showing the bolt in end elevation;

25 Fig. 3 is a front view of the refrigerator cabinet showing my improved latch;

Fig. 4 is a fragmentary sectional view of a refrigerator cabinet showing a modified form of my invention;

30 Fig. 5 is a sectional view along the line 5—5 of Fig. 4; and

Fig. 6 is a front view of a refrigerator cabinet showing the modified form of my improved latch.

Referring to the drawing, and more particu-

35 larly to Fig. 1, there is shown, for the purposes of illustrating my invention, a fragmentary portion of a refrigerator door 24 including a rectangular door frame 20, to which is fastened a facing member 21, which forms the front face of the door.

40 The space within the rectangular frame member 20 is filled with a suitable insulation 22, such as cork. The front face of the door is covered by the sheet metal covering 23 which is laid on top of the facing member 21 and which is preferably as

45 coated with a suitable coating material, such as lacquer or porcelain. The rear face of the door 24 is also provided with a suitable sheet metal covering 25 which is preferably coated with some suitable coating material such as porcelain. The

50 sides of the door are provided with a side facing strip 26 of some suitable material having a low heat conductivity. In this figure is also shown a portion of the door jamb 27 which is provided with a facing strip 28 upon its inner face.

55 The latch means for the door has a simple,

rugged construction. A passageway 29 is drilled into the side of the door 24 and into the adjacent portion of the rectangular door frame 20. A tubular slideway 30 is pressed into this passageway 29 and is provided with an integral flange 31 at its outer end which is fastened by means of screws 32 (see Fig. 2) to the rectangular frame member 20. A cylindrical bolt 33 is slidably mounted within the tubular slideway 30 and has a kerf at its projecting end which receives a suitable roller 34 which is mounted by means of a pin 35 which passes through the ears of the projecting end of the bolt 33.

5 A handle 37 of an ornamental shape is provided for operating the bolt 33. This handle projects 15 from the front of the cabinet and is pivoted to a suitable supporting plate 38 which is provided with turned down ears 39 for receiving a pin 40 which passes through the ears and the pivot point of the handle 37. An operating arm 41 extends 20 inwardly from the pivot point of the handle 37 through a slot 42 in the tubular slideway 30 into a recess 43 in the cylindrical bolt. A helical spring 44 is provided between the inner end of the bolt and the inner end of the tubular slideway for 25 forcing the bolt toward the keeper.

From the standpoint of external appearance, it is highly desirable to keep the marginal edge of a refrigerator cabinet unobstructed. For this reason a concealed keeper 46 is provided in the 30 inner face of the door jamb 27 which is hollowed out for this purpose. This position is particularly desirable because excellent support is provided directly by the door jamb. The keeper 46 is pro- 35 vided with an inclined face 47 for retracting the bolt 33 when the door is slammed shut. A notch 48 is provided in the keeper and has a wedge shape so that when the door is closed the roller 34 will press against the inclined side 49 of the keeper 46 and in this way holds the door tightly 40 closed. The door 24 is opened by grasping the handle and turning it counterclockwise with respect to the showing in Fig. 1 to cause the operating arm 41 to retract to pull the bolt 33 and its roller 34 from the notch 48 of the keeper 46 and 45 by the pull which naturally accompanies this pulling of the handle forward, the door is pulled open with comparative ease.

With the bolt mechanism concealed within the door, it is cooled because of its proximity to the cold inner portions of the refrigerator and there would be difficulty if external air should get into the bolt mechanism and be cooled below its dew point and moisture be deposited upon the bolt mechanism causing corrosion therein. This

moisture would also have a tendency to cause swelling of the rectangular frame 28 and the facing member 21. In order to avoid this objectionable occurrence, I provide a cup-shaped rubber sealing member 80 provided with flanges 81 which are held between the supporting plate 38 and the facing member 21. This cup-shaped member 80 is provided with an aperture 82 through which the operating arm projects. The rubber around the aperture is made especially thick so as to tightly grip the operating arm 41 so as to prevent any moisture from leaking at this point. By clamping the flanges of the cup-shaped rubber member and by having the aperture tightly fitting the operating arm, no moisture is allowed to enter the latch mechanism from this path. The shape of the rubber member may be altered to suit conditions. The bolt 33 fits with sufficient snugness in the tubular slideway 30 so as to prevent any great amount of air from entering the latch mechanism in this way. Furthermore, since there is a seal 83 provided between the facing member 21 and the door jamb 27, the external air does not have access to the outer end of the bolt 33. Consequently, only cold air from the interior of the refrigerator cabinet has access to the bolt 33. This cold interior air is below the temperature of the bolt mechanism and therefore no condensation will take place from the air from this source. Should the rubber member break, moisture would not have access to the insulation 22 since the passage 29 is blind and wholly within the rectangular door frame 28. An ornamental escutcheon plate 85 provided with an aperture 86 for receiving the handle 31 is employed for covering the supporting plate 38 and the cup-shaped rubber member 80 to give the latch a distinctive appearance.

In Fig. 4 there is shown a fragmentary sectional view of a refrigerator door 54 including a rectangular frame 50 and a facing member 51, fastened to the front side of the rectangular frame 50. Suitable insulation 52, such as cork, is provided within the rectangular frame 50 for insulating the door. A sheet metal covering 53, preferably provided with a suitable coating such as porcelain, is laid over the facing member 51 for covering the front surface of the door 54. This covering 53 is provided with a sunken groove 55 in which a tubular slideway 56 is fastened. Within the slideway 56 there is a cylindrical bolt 57 provided with a kerf at its outer end which receives a roller 58. The roller 58 engages a suitable keeper 59 which is fastened to the outer side of the door jamb 60. A suitable handle 61 is provided for retracting the bolt. This handle 61 is pivotally supported by means of the pin 62 upon a bracket 63 fastened by means of screws 64 to the outer face of the door and provided with upstanding ears 65 for receiving the pin 62. The bracket 63 is preferably brazed and sweated to the tubular slideway 56 to provide a unitary piece. The handle 61 has an operating arm 70 extending inwardly from the pivot pin 63 through a slot 67 in the outer portion of the tubular slideway 56 into a recess 69 provided for this purpose in the bolt 57. The operating arm 70 presses against the rear end of the recess 69 and retracts the bolt 57 and the roller 58 from engagement with the keeper 59 against the resilient force of the coil spring 71 which is provided between the

inner end of the bolt 57 and the inner end of the tubular slideway 56.

An ornamental escutcheon plate 90 is provided for covering the latch mechanism so as to give the latch a pleasing appearance. By sinking the latch mechanism into the door, the amount of projection of the handle and the keeper is reduced and because of the reduced moment arm, there is less strain upon the fastenings of the keeper.

While the form of embodiment of the invention as herein disclosed, constitutes a preferred form, it is to be understood that other forms might be adopted, all coming within the scope of the claims which follow.

What is claimed is as follows:

1. A latch for a refrigerator door including a bolt slidably supported upon the inside of the door, a slideway fastened to the door for slidably supporting the bolt, a pivoted handle projecting from the door and having means for operating said bolt, means mounted on the door for pivotally supporting said handle, and a flexible fluid tight sealing member having its edges sealed to the door and its central portion tightly fitting said bolt operating means for preventing the access of external air and moisture to said bolt.

2. A latch for a refrigerator door including a bolt slidably supported on the inside of the door, a slideway fastened to the door for slidably supporting the bolt, a pivotally mounted handle projecting from the door and having means connected thereto for operating the bolt, means mounted on the door for pivotally supporting said handle, a cup-shaped flexible fluid tight member having its edges clamped beneath the last mentioned means sealing the edges to the door and its central portion tightly fitting the bolt operating means for preventing the access of external air and moisture to the bolt.

3. A latch for a refrigerator door including a bolt slidably mounted upon the inside of the door, a slideway fastened to the door for slidably supporting the bolt, a handle pivoted to the door and projecting from the door, said handle having a finger extending into the door for operating the bolt, and a flexible fluid tight sealing member tightly fitting said finger for preventing the access of external air and moisture to said bolt.

4. A latch for a refrigerator door having an opening including, a pivoted handle passing through the opening, a spring actuated bolt, an arm on said handle for operating said bolt against spring tension, and a gasket of resilient material through which said arm extends for closing the opening about said arm.

5. A refrigerator latch including a pivoted handle, a latch means, a latch operating arm forming a part of said handle and extending into an opening, and a gasket of resilient material through which said arm extends to seal the opening about said arm regardless of the position of the handle.

6. A means for holding a door closed, the door having an opening therein, including a handle member extending into the opening and having a certain limit of movement therein, and a gasket of resilient material through which the handle extends yieldable with the movement of said handle, throughout its range of movement to seal said opening.

HAL W. MCPHERSON,
